UNITED STATES PATENT OFFICE.

TALBOT C. DEXTER, OF PEARL RIVER, NEW YORK.

PAPER-FEEDING MACHINE.

SPECIFICATION forming part of Letters Patent No. 605,089, dated June 7, 1898.

Application filed September 16, 1896. Renewed October 16, 1897. Serial No. 655,480. (No model.)

To all whom it may concern:

Be it known that I, TALBOT C. DEXTER, a citizen of the United States, residing at Pearl River, in the county of Rockland and State 5 of New York, have invented certain new and useful Improvements in Paper-Feeding Machines, of which the following is a specification.

My present invention relates to improvements in the class of machines designed to feed successively one sheet of paper at a time from a pile to a printing-press, paper folding or ruling machine, or other machine designed to operate upon the paper. In practice with 10 these machines it is very necessary to have the paper piled evenly in order to insure feeding the sheets forward squarely and to the same point. In fact, it has been found extremely difficult in some cases to start the 15 sheets squarely from the feeding-machine into the folding-machine or other machine to which the paper is fed owing to the fact that the push-fingers or feeding instruments are apt to slip more or less upon the surface of 20 the sheet. If the sheets are not started squarely from the feeding-machine, they will be fed out of the machine at an angle and are apt to catch in going into the folder or printing-press and result in destroying the 25 paper or in the interruption or injury of the machine. It will therefore be observed that it is very desirable to provide means by which the push-fingers or feeding instruments will act independently of each other for feeding 30 the sheets of paper forward exactly the same distance at each edge of the sheet and square the ends independently of each other. In an application filed by me November 22, 1897, 35 Serial No. 659,366, I cover, broadly, automatically-controlled frictional feeding instruments controlled by the sheet being fed off for accomplishing this result. It is the object of my present invention to accomplish 40 this same result by a different form of mechanism from that described and claimed in my above-named case. To this end I provide 45 means for automatically rendering the frictional engagement of the feeding fingers or instruments with the paper active or inactive without interfering with the uniform stroke of the feeding devices and without nec-

essarily elevating the feeding devices from the surface of the paper, such mechanism being under the control of automatic controlling devices operated by the passing sheets 55 of paper for rendering the frictional engagement of the feeding devices with the paper inactive when the advance edge of the sheet reaches a certain point and active again after the sheet has passed from the feeding-machine. I have stated that the feeding devices are not necessarily elevated from the surface of the paper in carrying out my invention; but the invention applies as well to such feeding devices that are elevated from the surface of the paper in making their return strokes as to those which are not so elevated.

The preferred mechanism for accomplishing the above result comprises two push-fingers or feeding-off fingers having journaled 70 in their forward ends frictional feed-rollers provided with ratchet-wheels with which engage suitable spring-released dogs or detents, said dogs or detents being operated against the action of their springs to cause them to 75 engage the ratchet-wheels by means of independent electromagnetic devices automatically controlled by electric contact devices supported in the path of the paper and operated by the passing sheets.

I prefer to employ my improved automatically-controlled feeding devices in combination with sheet-buckling devices and sheet-separating devices—such, for instance, as illustrated and claimed in my pending application, Serial No. 617,263, filed December 28, 1896, for improvements in paper-feeding machines.

In order that my invention may be fully understood, I will first describe the same with 90 reference to the accompanying drawings and afterward point out the novelty with more particularity in the annexed claims.

In said drawings, Figure 1 is a plan view of a paper-feeding machine having my improvements applied thereto. Fig. 2 is a central longitudinal sectional view of the machine and showing the automatic feeding-fingers in operative position. Fig. 3 is a similar sectional view having parts broken away, showing the feeder-fingers in elevated inoperative position. Fig. 4 is an enlarged detail sec-

tional view showing one of the automatic electric controlling devices of the feeding-fingers and the sheet-separating device. Fig. 5 is an enlarged detail longitudinal sectional view 5 of the same. Fig. 6 is a detail side elevation of one of the feeding-fingers. Fig. 7 is a front elevation of the same. Figs. 8 and 9 are enlarged perspective views of the automatic controlling device and the paper-feeding device.

1 is the main frame of a feeding-machine, and 2 is a vertically-movable table of the machine, upon which is piled paper P to be fed from the machine. The table is raised 15 automatically by means of the vertical screws 3 working in nuts 4, attached to the table. The mechanism for transmitting motion to the screws is immaterial and is not described.

5 represent sheet-buckling devices which 20 are supported above the pile of paper adjacent to the rear corners. These buckling devices are adapted to be operated in any suitable manner for separating the rear edges of the sheets from the remainder of the pile before the feeding-off devices are brought into 25 operation. The sheet-buckling devices are well known in this art, and as those employed in my present machine may be of any of the well-known forms I have not specifically described this part of the mechanism.

Supported at the forward edge or delivery end of the machine are suitable beds 10, having hard-rubber surfaces 11. Over these beds are supported friction-pads 12, which are reciprocated horizontally parallel with the line of feed and movable vertically to and from the bed, respectively, at the rear and front ends of their horizontal strokes. These pads are formed of soft rubber and are supported 35 at the lower ends of the levers 15, which are pivoted to slides 16, riding on the guides 17, secured by hanger-brackets 18 to the cross-bar 19, fastened to the sides of the main frame 1. These sheet-separating devices are 40 essentially the same as covered by my application above referred to, Serial No. 617,263, and a further description of them and the mechanism for operating them for effecting the separation of two or more sheets which 45 may have been fed forward simultaneously will not be necessary. Such sheet-separating devices at the delivery end of the feeding machine are also preferably employed in connection with my improved automatic feeding-off devices; but they are not essential.

The above-described parts of the mechanism do not constitute my present invention, except in combination with the features hereinafter described, for in my above-named application, Serial No. 617,263, I have claimed, broadly, the combination of a frictional retarding-bed arranged at the delivery end of the machine, feeding-off fingers operating above a pile of sheets for feeding the sheets 50 from the pile onto said retarding-bed, and a separator-pad operating alternately with the feeding-off fingers and adapted to engage the

front marginal portion of the sheets above the retarding-bed only for separating said sheets from any chance underlying sheets 70 and feeding them forward from the machine.

25 is a rock-shaft suitably journaled in the machine-frame and operated in any suitable manner.

26 is a rock-arm keyed to and depending 75 from the shaft 25, and 27 is the paper-feeding finger or feeding-off finger journaled to the lower end of rock-arm 26.

28 is the friction feed-roll, freely journaled in the forward bifurcated end of the feeding-finger 27, and 29 is a ratchet-wheel keyed to the journal 28^a of the roll 28.

30 is a sliding dog or detent sliding in bearing 31 on the arm 27 and having a nose 30^a, which is adapted to be thrown into engagement with the ratchet-wheel 29.

32 is a spiral spring engaging the arm 27 and the dog 30 and holding the dog 30 normally out of engagement with ratchet 29 to allow the feed-roll 28 to rotate freely in the 90 arm 27.

35 is a journal-pin secured in the lower end of rock-arm 26, upon which the arm 27 is loosely journaled.

38 is a cam also journaled upon rod 35 and secured to arm 27 to move with it.

36 is a spiral spring engaging the pin 35 at one end and the arm 27 at its other end for affording the necessary downward pressure to the arm 27 and feed-roll 28.

40 is a lever pivoted to arm 26 at one side and provided with a spring 41 for holding it in contact with the cam 38.

In Figs. 3 and 6 the spring 41 is shown secured to rock-arm 26 below the pivot of lever 40, while in Fig. 9 the spring is secured to said rock-arm above the pivot of lever 40; but in both arrangements of the spring it engages lever 40 above its pivot for holding its lower end in engagement with cam 38.

In Fig. 2 the spring 41 is omitted.

42 is a pin adapted to engage the nose of cam 38 when the feeding-finger reaches the end of its forward stroke, thereby elevating the feed-roller 28 from the surface of the paper and causing the spring-pressed lever 40 to engage the notch 38^a of the cam for holding the feed-roller in elevated position until it is again ready to make its forward stroke. When the feeding device reaches the end of its backward stroke, a stop 43 engages the upper end of lever 40 and releases the cam 38, thereby allowing the spring 36 to again throw the arm 27 and feed-roll 28 into lowered position.

45 is an armature-lever pivoted at 46 on one side of rock-arm 26 and pivotally engaging the dog 30 at its lower end 47.

48 is an armature mounted upon the upper end of lever 45.

50 is an electromagnet supported upon a curved arm 49 of the rock-arm 26 in proper relation to the armature 48.

Secured to one side of the bed 10 of the

sheet-separating device is a block 55, of fiber or other insulating material, formed with a longitudinal groove 56 in its upper face.

60 is a block or plate secured to the under side of the guide 17, said block being formed with bracket-arms 61, in which is pivoted the lever 62. The bearings 63 of lever 62 are insulated from the bracket-arms 61.

64 is an adjustable contact screw or pin seated in the block 60, provided with lock-nuts 65.

62^a is the contact end of the lever 62, adapted to normally engage the contact 64. The forward lower end of the controlling-lever 62 is curved at 62^b, said curved end resting normally in the slot 56.

70 is a battery, and 71 is an electric circuit including the electromagnet 50, battery 70, contact 64, and lever 62. When there is no paper passing under the contact-lever 62, the circuit is closed, energizing the magnet 50 and causing it to attract armature 48 and cause the dog 30 to engage the ratchet-wheel 29 and prevent the rotation of the feed-roll 28.

75 It will be observed that two sets of feeding devices are arranged upon the pile of paper transversely to the line of feed and that each feeding device is provided with an automatic electric controlling device for rendering it inactive at the moment the advance edge of the paper directly in front of said device reaches the line of register.

The operation of the device may be briefly described as follows: The buckling devices 35 at the rear edge of the sheet first separate the rear corners of the top sheet from the pile. The feeding-fingers then come into play and engage the sheet for feeding it forward. As there has been no sheet advanced 40 from the pile, the circuit will be closed by reason of the levers 62 being in contact with the pin 64. This will hold the dog 30 in engagement with ratchet 29 and prevent the rotation of feed-roll 28, so that as the push-fingers are advanced they carry the sheet along until the front edge has advanced sufficiently far to lift the lower curved ends of levers 62, which break the magnetic circuit and allow the springs 32 to disengage the dogs 45 50 from ratchet-wheels 29 and allow the rollers 28 to rotate over the paper until the feeding-fingers have finished their stroke. If the feeding-fingers are provided with the mechanism for elevating them for their rear stroke, 55 this operation will next occur; but if the feeding-fingers are not elevated the rollers will revolve over the paper on the backward stroke of the feeding-fingers, and as they freely rotate they will not interfere with the movement of the sheet out of the machine. As 60 soon as the forward edge of the sheet reaches the contact-levers 62 the sheet-separating blocks are brought into play and insure the separation of the upper sheet from the next 65 lower if the latter has happened to follow it forward, and the drop-rollers or other suit-

able devices then engage the sheet and carry it out of the machine.

If the sheet has been started forward unevenly, it will be observed that the controlling device at one side or the other will be actuated sooner than the other controlling device, causing its feeding device to be rendered inactive first and allow the other feeding device to feed the opposite side of the paper forward until the sheet is squared. If two sheets should be disengaged by the bucklers and be fed forward by the push-fingers at one time, so that their front edges overlap the lower bed of the separator, one sheet 80 would remain on the separator-bed under the curved ends of levers 62 after the first had been moved by the separator and carried out of the machine. This remaining sheet would thus prevent the circuits being closed, so that 85 in the succeeding stroke of the feeding devices the rollers would freely revolve and roll over the surface of said sheet and would not feed it forward, but would leave it to the action of the separator and other devices which 90 carry the sheet out of the machine. The same thing would happen if there had been several sheets fed forward at one time, all but one (the top sheet) of the several sheets being allowed to remain in practically the 95 same position to which they were brought by the push-fingers and afterward successively moved forward and out of the machine by the separator and drop-rollers. Now if, after several sheets had been fed forward to the 100 separator, in making the next stroke the push-fingers would again advance these several sheets, they would be pushed beyond the separator. Therefore there would be no opportunity of separating them and the entire 105 balance of the number would be fed from the machine, whereas by my improved method, it will be understood that where several sheets are fed forward by the push-fingers and only one at a time fed by the separators, the remaining sheets will cause the electric contacts to remain broken so that the push-fingers will be deprived of their ability to push forward these sheets, owing to the fact that the 110 rollers will revolve on the paper as the magnets are deprived of their power for locking them. It will therefore be observed that my automatically-controlled feeding-off devices are indispensable to the perfect operation of 115 a feeding-machine of this class.

I am aware that it has been proposed to control the action of sheet-combing devices by the movement of the sheet being fed forward, and I do not claim such a structure. I am also aware that it is old to provide a feed-finger 125 with a roller which is adapted to rotate freely on the rearward stroke of the feed-finger and to bind and be held against rotation on its forward stroke for effecting the feed of the sheet. I do not claim such a structure. In contradistinction to these well-known structures my invention comprises suitable feeding devices 130

having means controlled by the movement of the sheet for automatically rendering the frictional engagement of the feeding devices with the sheet active or inactive, according to the position of the sheets of paper, thereby perfectly squaring the forward edge of each sheet as it is fed forward and automatically feeding the sheets successively from the machine. In my above-named application, Serial No. 659,366, I have claimed, broadly, the automatically-controlled frictional feeding instruments, as distinguished from combing devices, whereas in my present application my claims cover such automatically-controlled feeding devices which are rendered inoperative or inactive independently of their elevation from the surface of the paper, whether or not they are constructed to move out of and into contact with the paper at the ends of their stroke. Having thus described my invention, what I claim as new, and desire to secure by Letters Patent, is—

1. The combination, in a paper-feeding machine, of suitable feeding devices, having a normally-active frictional engagement with the paper on their forward stroke, means for imparting a uniform stroke to the feeding devices, and means for automatically rendering the frictional engagement of the feeding devices inactive at certain points on their forward stroke without elevating them from the paper or arresting their uniform motion, said automatic means being controlled by the advance edge of the paper being fed off, substantially as set forth.

2. The combination, in a paper-feeding machine, of suitable feeding devices, means for imparting a uniform feeding motion thereto, and suitable electric controlling devices operated by a passing sheet for rendering the feeding devices active or inactive according to the position of the sheet being fed off and without interfering with or interrupting their uniform feeding motion or elevating the feeding devices from the paper, substantially as set forth.

3. In a paper-feeding machine for automatically moving sheets of paper from a pile, the combination of a feeding-finger, means for operating it, a friction feed-roller journaled in said finger and adapted to bear upon the paper, an automatic device for holding said roller against rotation to cause it to move the paper, and suitable means operated by the moving sheet for automatically controlling the action of said automatic device causing it to release the roller to free rotation over the paper when the sheet has a certain position, and to hold the roller against rotation when in another position to cause it to feed the succeeding sheet, substantially as set forth.

4. In a paper-feeding machine for automatically moving sheets of paper from a pile, the combination of two feeding-fingers arranged transversely of the line of feed a suitable distance apart above the pile of paper, means

for operating said feeding-fingers in parallel planes, feed-rollers journaled in said feed-fingers and adapted to bear upon the paper, independent automatic devices for holding the respective rollers against rotation to cause them to move the paper, and suitable independent controlling devices operated by the moving sheet for automatically controlling said automatic holding devices and causing them to free the roller for rotation and thereby arrest the feed of each roller when the edge of the sheet in front of it reaches a certain point, substantially as set forth.

5. In a paper-feeding machine, the combination of a feeding-finger, a friction feed-roll journaled in said finger, a dog or detent carried by the finger and adapted to hold the roller against rotation, and suitable automatic means operated by a moving sheet for controlling the operation of the dog and consequent action of the feed-roll, substantially as set forth.

6. In a paper-feeding machine, the combination of a feeding-finger, a friction feed-roll journaled in the finger, a ratchet-wheel secured to the journal of the feed-roll, a spring-released dog or detent carried by the feed-finger and adapted to be moved into engagement with the ratchet-wheel for holding the roll against rotation, and a suitable automatic device controlling the dog or detent and operated by the advance edge of the sheet being fed off for releasing the dog from engagement with the ratchet to allow the rotation of the roll, substantially as set forth.

7. In a paper-feeding machine, the combination of a feeding-finger, a friction feed-roll journaled in the feed-finger and provided with a ratchet-wheel on one of its journals, a dog or detent carried by the feeding-finger and adapted to engage the ratchet, an electromagnetic device adapted to move the dog into engagement with the ratchet, and an electric-contact-controlling device operated by a passing sheet for controlling the action of the electromagnetic device, substantially as set forth.

8. In a paper-feeding machine, the combination of a feeding-finger, a rock-arm upon which said finger is mounted, a friction feed-roll journaled in said finger and having a ratchet-wheel secured to its journal, a dog or detent supported on the feed-finger and adapted to engage the ratchet, an armature-lever pivoted to the rock-arm and engaging the dog or detent and carrying an armature, an electromagnet supported on the rock-arm, and an electric-contact-controlling device operated by a passing sheet for controlling the action of the electromagnet, substantially as set forth.

9. In a paper-feeding machine, the combination of a feeding-finger, a friction feed-roll journaled in said finger and having a ratchet-wheel secured to its journal, a dog or detent supported upon the finger and adapted to engage the ratchet-wheel, a pivoted lever engaging the dog or detent, an armature on said

lever, an electromagnet, a normally-closed electric circuit including the electromagnet, and a circuit making and breaking arm or lever in said circuit supported in the path of the paper to be operated thereby, substantially as set forth.

10. In a paper-feeding machine, the combination of a feeding-finger, a friction feed-roll journaled in the feed-finger, an electromagnetic device for holding the feed-roll against rotation in the feed-finger, an electric battery, a contact-point, a contact-lever supported in the path of the paper formed with a curved lower end adapted to be engaged by the paper, and an electric circuit including the magnetic device, the battery and contacts, substantially as set forth.

11. In a paper-feeding machine, the combination of a feeding-finger having a friction feed-roll journaled in it, means for automatically elevating the feed-finger from the surface of the paper at the end of its forward stroke and for lowering the feed-finger upon the paper at the end of the rear stroke, means for holding the roller against rotation in the feed-finger, and an automatic controlling device operated by the passing sheet for regu-

lating the roller-holding device, substantially as set forth.

12. In a paper-feeding machine, the combination of a paper-feeding finger having a feed-roll journaled in its end, a suitable device for holding the roll against rotation, an automatic controlling device operated by a passing sheet for regulating the action of the roller-holding device, and suitable buckling mechanism for separating the rear corners of the sheet from the pile, substantially as set forth.

13. In a paper-feeding machine, the combination of paper-feeding fingers having friction feed-rolls journaled in their ends, means operated by the passing sheet for automatically holding said rollers against rotation or allowing them to rotate, with a sheet-separator comprising a bed disposed in front of the delivery end of the machine, and a friction-pad reciprocating over said bed and moving vertically at the ends of its stroke, substantially as set forth.
